[57] CLAIM

The ornamental design for a telephone note holder, or the like, substantially as shown and described.

DESCRIPTION

FIG. 1 is a perspective view of a telephone note holder showing my new design, the dotted line showing of a telephone being for illustrative purposes only;

FIG. 2 is an enlarged scale front elevational view of the telephone note holder;

FIG. 3 is a side elevational view thereof as seen from line 3—3 of FIG. 2;

FIG. 4 is an elevational view thereof as seen from line
4—4 of FIG. 3;

FIG. 5 is a plan view thereof as seen from line 5—5 of
FIG. 3; and

FIG. 6 is a bottom plan view thereof as seen from line
6—6 of FIG. 3.
